Patented May 23, 1922.

INVENTOR

FRANK L. RUZICKA,
by Arthur C Eckert ATTORNEY.

UNITED STATES PATENT OFFICE.

FRANK L. RUZICKA, OF ST. LOUIS, MISSOURI.

STAKE LOCK.

1,416,881.

Specification of Letters Patent. Patented May 23, 1922.

Application filed June 4, 1921. Serial No. 474,935.

To all whom it may concern:

Be it known that I, FRANK L. RUZICKA, a citizen of the United States of America, residing at 7th Street and Cass Avenue, in the 5 city of St. Louis and State of Missouri, have invented certain new and useful Improvements in Stake Locks, of which the following is a specification.

The object of my invention is to make 10 a stake pocket and stake with a lock for securing the stake in the stake pocket. It is highly advantageous to be able to lock the stake in the stake pocket so as to prevent loss through disengagement of the stake. 15 The lock must be simple in construction, lend itself readily to multiple construction, must be positive in its action, must securely hold the stake in the stake pocket in an upright position, and prevent the stake from 20 rocking in the stake pocket. The lock must be readily accessible, easily operated and reasonably concealed so as to remove the temptation of an unauthorized person from 25 removing the stake from its pocket. The lock must be durable, simply made and permit of simple repair and replacement of parts. The lock must be made so as not to appreciably increase the weight or bulk 30 of the stake or pocket, must be made of few parts and so positioned in the stake that the lock will not be mutilated with an abuse of the stake. With this and other objects in view, my invention has relation to certain 35 novel features of construction and arrangements of parts as will hereinafter be more fully described, pointed out in the claims and illustrated in the drawings in which—

Fig. 1 is a perspective view of my stake pocket and stake with the lock showing the 40 stake in erect position in its pocket.

Fig. 2 is a front elevation of my stake and stake pocket together with the lock, and

Fig. 3 is a longitudinal sectional elevation 45 of my stake, stake pocket, lock, and concealing plate.

Numeral 5 designates the section of the side rail of a wagon frame, numeral 6 designates a stake pocket secured to the rail 5 by 50 means of the bolts 7. Numeral 8 designates a portion of a stake which fits into the pocket 6 in the conventional manner. In the stake pocket 6, on its external front surface is formed a rectangular notch 9. 55 Numeral 10 designates a spring element which is secured to the stake 8 by means of

the nut and bolt 11. In the stake 8 is formed a longitudinal depression 12 into which the spring element 10 fits so that its lower free end permits of a movement in 60 and out of the longitudinal depression 12. The lower end of the spring element 10 is bent under the bottom of the stake 8 and counter-sunk so as to form a flush surface with the bottom of the stake 8. On the 65 spring element 10 near its lower and free end is formed a triangular prismatic projection 10', having a base, the width of which is equal to the width of notch 9 and the length of which is equal to the length of 70 the notch 9. It will be seen that by depressing the spring element 10 manually by holding it at the portion extending below the stake pocket 6 that the triangular prismatic projection 10' may be moved in and 75 out of engagement with the notch 9. When the engagement is established the stake 8 is locked in the stake pocket 6. When the engagement is broken by compressing the spring element 10, the stake may be easily 80 disengaged from its stake pocket in the conventional manner. It is highly advantageous to have the fit between the triangular prismatic projection 10' and the notch 9 exact so that there can be no lateral movement 85 between them because a precluding of this lateral movement precludes the lateral movement of the stake 8 in the pocket 6. If this lateral movement is not prevented, the stake 8 will be subject to wear and disintegration at the portion of it that comes 90 in contact with the stake pocket 6.

Numeral 13 designates a portion of a concealing plate which is secured over the external face of the pocket 6 thereby obscuring the triangular prismatic projection 10' and the notch 9. This concealing plate usually runs around the entire wagon rail 5 and performs a similar function at each stake pocket.

What I claim and mean to secure by Letters Patent is:

1. In combination with a stake pocket having a notch, a stake having a projection, the projection on said stake and the notch 105 in said stake pocket being so positioned on their respective elements as to permit of selective engagement between said projection and said notch, and means of concealing the notch of said stake pocket, and the 110 projection on said stake.
2. In combination with a stake pocket

having a notch formed therein, a stake having a longitudinal depression formed therein for a portion of its length, a spring element having a projection formed thereon, 5 said spring element secured at its one end in the depression in said stake and free to vibrate at its loose end, said stake pocket and stake being so formed as to permit the placing of said stake in said stake pocket

and the selective engagement of the projection on said spring element with the notch in said stake pocket, the free end of said spring element being bent flush with the bottom of said stake, a plate secured over the external surface of said stake pocket. 10

In testimony whereof I affix my signature. 15

FRANK L. RUZICKA.
